DESIGN FOR A VANITY OR THE LIKE

Frank McIntosh, New York, N. Y., assignor to Letheric, Incorporated, New York, N. Y., a corporation of New York

Application January 30, 1948, Serial No. 144,176

Term of patent 7 years

(Cl. D86—10)

To all whom it may concern:

Be it known that I, Frank McIntosh, a citizen of the United States, residing at New York, in the county of New York and State of New York, have invented a new, original, and ornamental Design for a Vanity or the like, of which the following is a specification, reference being had to the accompanying drawing, forming part thereof.

Fig. 1 is a top plan view of a vanity or the like embodying my new design; and

Fig. 2 is a front elevational view thereof.

I claim:

The ornamental design for a vanity or the like, substantially as shown.

FRANK McINTOSH.
